Primary Examiner — Barbara G Fox*Assistant Examiner* — Mary C Ramirez(74) *Attorney, Agent, or Firm* — Amster, Rothstein & Ebenstein LLP(57) **CLAIM**

The ornamental design for a photo booth, as shown and described.

DESCRIPTION

FIG. 1 is a top perspective view of a photo booth showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom plan view thereof; and,

FIG. 8 is a sectional view thereof taken along line 8-8 of FIG. 1.

The broken lines in the drawings depict portions of the photo booth that form no part of the claimed design. The broken lines showing the table in the center of the photo booth depict environmental subject matter and form no part of the claimed design.

1 Claim, 7 Drawing Sheets(58) **Field of Classification Search**
